CLAIM

The ornamental design for a base for bathing area, as shown and described.

DESCRIPTION

FIG. 1 is a top, front perspective view of a base for bathing area embodying my new design;

FIG. 2 is a top plan view thereof;

FIG. 3 is a front elevational view thereof;

FIG. 4 is a rear elevational view thereof;

FIG. 5 is a right side elevational view thereof, the left side elevational view being a mirror image of the right side shown; and,

FIG. 6 is a cross-sectional view thereof taken along line 6—6 of FIG. 2.

The broken line representations of a mounting environment in FIG. 1, of a hole in FIGS. 1, 2, 4, 5, and 6, and of support structure in FIGS. 5 and 6, are for the purpose of illustration only, and form no part of the claimed design.
